United States Patent Office

Des. 198,609
Patented July 7, 1964

198,609

SAILBOAT

Kent Hamilton, Rancho Cordova, Calif., and Henry C. Grabbe, 3876 Fair Hill Road, and Richard S. Zimmerman, 4928 Vir Mar St., both of Fair Oaks, Calif.; said Hamilton assignor to said Grabbe and said Zimmerman

Filed Mar. 18, 1963, Ser. No. 74,009

Term of patent 3½ years

(Cl. D71—1)

Fig. 1.

Fig. 2.

Fig. 4.

Fig. 3.

Fig. 5.

FIG. 1 is a side elevational view of a sailboat, showing our new design;

FIG. 2 is a perspective view from astern;

FIG. 3 is a bottom plan view;

FIG. 4 is a bow elevational view; and

FIG. 5 is an elevational view from astern.

The dominant features of our design reside in the portions shown in full lines.

We claim:

The ornamental design for a sailboat, as shown and described.
